CLAIM

The ornamental design for a shoulder lunch tote, as shown and described.

DESCRIPTION

FIG. 1 is a front elevation view of the present invention, the rear side being a mirror image thereof, shown in a 'filled use' form.

FIG. 2 is a left side elevation view of FIG. 1, the right side being a mirror image thereof.

FIG. 3 is a top plan view of FIG. 1; and,

FIG. 4 is a bottom plan view of FIG. 1.

The dashed lines shown for seams, stitching, piping, bottom crimp, and zipper are provided for environmental purposes only and form no part of the claimed design.
